Primary Examiner — Susan Bennett Hattan*Assistant Examiner* — Omeed Agilee(74) *Attorney, Agent, or Firm* — Frost Brown Todd LLC(57) **CLAIM**

The ornamental design for an armrest, as shown and described.

DESCRIPTION

FIG. 1 is a left side perspective view of an armrest showing our new design;

FIG. 2 is a right side perspective view of the armrest of FIG. 1;

FIG. 3 is a left side elevational view of the armrest of FIG. 1;

FIG. 4 is a right side elevational view of the armrest of FIG. 1;

FIG. 5 is a back elevational view of the armrest of FIG. 1; FIG. 6 is a front elevational view of the armrest of FIG. 1; FIG. 7 is a top plan view of the armrest of FIG. 1; and, FIG. 8 is a bottom plan view of the armrest of FIG. 1. The broken lines in the drawing depict portions of the armrest that form no part of the claimed design.
